UNITED STATES PATENT OFFICE.

JOHN M. LEMMON, OF DES MOINES, IOWA.

WASHING-MACHINE.

SPECIFICATION forming part of Letters Patent No. 739,093, dated September 15, 1903.

Application filed June 26, 1903. Serial No. 163,278. (No model.)

To all whom it may concern:

Be it known that I, JOHN M. LEMMON, a citizen of the United States, residing at Des Moines, in the county of Polk and State of Iowa, have invented certain new and useful Improvements in Washing-Machines; and I do hereby declare that the following is a full, clear, and exact description of the same, reference being had to the annexed drawings, making a part of this specification, and to the letters of reference marked thereon.

The present invention has for its object to provide a washing-machine that will be easy in operation, will not injure the fabric, and be simple and strong in construction and the operating parts effective in removing the dirt from the clothes without undue friction thereon.

The invention consists in a washing-machine constructed substantially as shown in the drawings and hereinafter described and claimed.

Figure 1 of the drawings is a sectional elevation of a washing-machine embodying my invention; Fig. 2, a side elevation thereof, showing the tub-support in section; Fig. 3, a top plan view showing the cover and rubber partly broken away and the wringer-arm in position in dotted lines; Fig. 4, a detail perspective view showing the upper end of the standard and its connections; Fig. 5, a detail sectional view taken centrally through the standard, the yoke, and the arm, to which the rubber is connected, as shown on line 5 of Fig. 4 of the drawings.

In the accompanying drawings, A represents a suitable stand or support of any desirable construction and provided with sectional cross-braces, each brace comprising two sections B C, held together by screw-bolts *a* and nuts *b*.

Any suitable means may be substituted for that shown to support the rotatable shaft in an upright position, as I do not desire it to be understood that the invention is limited to the sectional cross-braces, as said braces may be variously modified or changed in construction without in any manner affecting the essential features of the invention.

The shaft D is suitably connected to the under side of a tub E for containing the water and suds, said shaft being rigidly connected

to the tub, so that it will rotate therewith or the shaft remain stationary as a support for the tub while the latter rotates, this being left to the best judgment of the manufacturer.

The tub E, which may be of any suitable size, form, and construction, is provided with a perforated bottom F, having radial ribs *c* upon its upper side, as shown in Fig. 1 of the drawings, said bottom being raised above the bottom of the tub the required distance to present a space for the settlement of dirt, this false bottom resting upon cleats *d*, secured to the tub by means of screw-bolts *e* and thumb-nuts *f*.

A presser-head G is disposed above the perforated false bottom F and is provided upon its under side with radial ribs *g*, the ribs upon the perforated false bottom and the ribs upon the presser-head coming in contact with the clothes placed between them. Upon the upper side of the presser-head G are secured radial braces *h* to give strength and rigidity to the head, said head being suitably connected to an upright shaft H, which in turn is adjustably connected to the free end of a horizontal arm I. Any means may be employed for adjustably connecting the shaft to the arm, which shaft is also removable therefrom, as desired, and the arm is adjustably connected to the upper end of an upright standard J.

The means preferably employed for rendering the shaft H and the arm I adjustable consists of the metal yokes *i j*, connected to the respective ends of the arm, and through these yokes extend the shaft and the standard J, respectively. The yoke *i* is clamped tightly around the end of shaft by means of the bolts *k* and nuts *l*, and when the shaft is adjusted to the required height the bolts are tightened to bring the yoke tightly against the sides of the shaft to hold it in its adjusted position, the shaft being capable of removal by loosening the yoke when circumstances require the removal thereof. In the present instances I have shown the metal yoke *j* formed with open slot *m* for engaging the end of a screw-bolt *n*, which extends through the end of the standard J and is provided with a thumb-nut *o*. (Shown more clearly in Fig. 5 of the drawings.)

The arm I may be adjustable upon the

standard J by engaging the bolt n in any one of the perforations p, or any suitable means may be employed to render the arm adjustable as found best adapted to the purpose, 5 as I do not wish to be understood as limiting my invention to any particular means of rendering the shaft adjustable upon the standard or the shaft H adjustable upon the arm, as any well-known means may be employed for this purpose.

A metal bar or rod K is detachably connected to the frame or support A and is provided with a suitable handle or hand-grasp at its upper end to serve as a lift for the 15 washing-machine. This bar or rod K, in connection with the standard J, provides means by which the machine can be lifted and moved from place to place as circumstances require, and when not in use the bar 20 or rod may be shoved back through the hole in the frame.

The standard J is secured to the frame A and is provided at its upper end with a wire loop q and a suitable latch L, secured to the standard 25 by means a nut r, the screw-threaded end of the loop extending through the latch and the nut engaging therewith, means being thus provided for attaching a wringer-arm M to the standard when a wringer is to be used 30 after the washing is completed, said wringer-arm extending through a wire loop and engaging the latch. The wire loop q is of such size as to leave space or room for the arm to be moved to disengage the latch and to be 35 swung around in position when a wringer is to be used, as shown in dotted lines of Fig. 3 of the drawings, the latch securely holding the arm in position when not in use.

The wringer-arm M is provided with suitable fasteners N of any well-known construction 40 that will admit the wringer being attached to the arm when required for use, said arm having a saddle O to engage the rim of the tub E to hold the arm steady and also 45 providing a suitable hooked rod P to engage an eye s upon the tub as an additional means for holding the arm steady during the process of wringing.

The tub E is provided with a suitable cover 50 Q, which has a hinged door R, whereby access may be had to the interior of the tub without removing the cover, said cover being held stationary while the tub revolves through the medium of the flat-sided shaft H, which extends up through a correspondingly-shaped 55 opening in the cover.

The tub E is provided with suitable handles S, diametrically opposite each other, so that

the tub can be given a semirotary reciprocating motion, necessary to give the clothes the 60 agitation to remove the dirt. To supply or remove the clothes from the tub, the nut o is first loosened and the arm II, with the presser-head G, is detached, as is also the arm I detached from the standard J, when the presser-head, with the shaft II and arm I, may be removed and replaced in like manner, the yoke j, with its open slot m, enabling the arm to be readily disengaged after loosening the nut o. The tub may be emptied of the dirt, water, 70 and suds through a suitable hole temporarily closed by a plug t. (Shown in Fig. 2 of the drawings.)

If desired, the standard J may be provided with a suitable handle T for convenience of 75 moving the frame or standard A or for any other purpose in which a handle would be found useful.

I do not desire to be understood as limiting my invention to the precise construction 80 shown, as it is evident that many changes or modifications in the several details of construction may be resorted to without in any manner affecting the essential features of the invention, and any such changes as would 85 come within ordinary mechanical judgment may be made and still preserve the more important features of the machine.

A washing-machine embodying my invention is both strong and durable, and the several parts may be separated and placed in a compact form for storage or transportation, and when set up a washing-machine is provided that will successfully do its work quickly and expeditiously, nothing interfering with 95 the full and free swing of the tub.

Having now fully described my invention, what I claim as new, and desire to secure by Letters Patent, is—

A washing-machine comprising a suitable 100 frame or support, a rotatable tub supported thereby, a perforated false bottom located in the tub above the bottom thereof, a presser-head and an upright shaft connected thereto, a horizontal arm and yokes upon the ends 105 thereof with means for adjustably connecting said arm to the shaft of the presser-head and to a suitable standard projecting from the frame or support, substantially as and for the purpose described.

In testimony whereof I affix my signature in presence of two witnesses.

JOHN M. LEMMON.
